(57) **CLAIM**

The ornamental design for an intrusion detection device, as shown and described.

DESCRIPTION

FIG. 1 provides a front perspective view of an intrusion detection device.

FIG. 2 provides a front elevational view of an intrusion detection device.

FIG. 3 provides a back elevational view of an intrusion detection device.

FIG. 4 provides a left side elevational view of an intrusion detection device.

FIG. 5 provides a right side elevational view of an intrusion detection device.

FIG. 6 provides a top plan view of an intrusion detection device; and,

FIG. 7 provides a bottom plan view of an intrusion detection device.

The broken lines showing seams, joints, and functional elevation are for illustrative purposes only and form no part of the invention.
